J. Q. PARIS,
POWER TRANSMITTING DEVICE,
APPLICATION FILED JUNE 13, 1917.

1,260,795.

Patented Mar. 26, 1918.

Attorney

UNITED STATES PATENT OFFICE.

JOHN QUINCY PARIS, OF ROCKMART, GEORGIA, ASSIGNOR OF ONE-FOURTH TO NIMROD V. PARIS AND ONE-FOURTH TO HENRY L. PARIS, BOTH OF POLK COUNTY, GEORGIA.

POWER-TRANSMITTING DEVICE.

1,260,795.

Specification of Letters Patent. Patented Mar. 26, 1918.

Application filed June 13, 1917. Serial No. 174,585.

To all whom it may concern:

Be it known that I, JOHN QUINCY PARIS, a citizen of the United States, residing at Rockmart, in the county of Polk and State of Georgia, have invented certain new and useful Improvements in Power-Transmitting Devices, of which the following is a specification, reference being had to the accompanying drawings.

10 This invention relates to certain improvements in power transmitting devices and it is an object of the invention to provide a device of this general character having novel and improved means whereby the same may be readily and conveniently coupled with the crank shaft of an automobile or with the driving shaft of other motors.

It is also an object of the invention to provide a novel and improved device of this 20 general character including a flexible and extensible mandrel whereby the device will be substantially free of the jars or vibrations incident to the motor with which the mandrel may be operatively connected.

25 A still further object of the invention is to provide a novel and improved device of this general character especially designed and adapted for use in connection with an internal combustion engine together with means whereby the mandrel of the device 30 may be operated to effect the requisite cranking of the engine.

Furthermore the invention has for an object to provide a novel and improved device 35 of this general character including a mandrel capable of movement in a direction angular to its axis of rotation so that said mandrel may be operatively connected with a driven element without the necessity of 40 employing a clutch mechanism.

The invention consists in the details of construction and in the combination and arrangement of the several parts of my improved power transmitting device whereby 45 certain important advantages are attained and the device is rendered simpler, less expensive and otherwise more convenient and advantageous for use, all as will be herein-after more fully set forth.

50 The novel features of the invention will hereinafter be definitely claimed.

In order that my invention may be the better understood, I will now proceed to de-

scribe the same with reference to the accompanying drawings, wherein—

Figure 1 is a view in elevation of a power transmitting device constructed in accordance with an embodiment of my invention, the mandrel included therein being shown in section;

Fig. 2 is a view in top plan of my improved power transmitting device as herein embodied with portions omitted;

Fig. 3 is a fragmentary view partly in elevation and partly in section illustrating the connection between the outer end portion of the mandrel and the drive shaft of a motor of an automobile or the like;

Fig. 4 is a sectional view taken substantially on the line 4—4 of Fig. 3; and

Fig. 5 is a sectional view taken through the inner end portion of the coupler and illustrating the means for connecting the same to the drive shaft of the motor.

As disclosed in the accompanying drawings, F denotes a frame structure including horizontally disposed parallel beams 1 arranged in predetermined spaced relation. The beams 1 are provided with the upstanding blocks 2 in longitudinal spaced relation and which support the rods 3, said rods being capable of detachable engagement with the blocks but anchored thereto preferably through the medium of the set screws 4.

Slidably engaged with the rods 3 are the transversely aligned bearings 5 which rotatably support a section 6 of the mandrel M. As herein embodied, the mandrel M comprises three sections 6, 7 and 8, the adjacent end portions of which being operatively connected through the medium of the universal joint 9.

The intermediate section 7 comprises two telescopically engaged members 10 and 11. The outer member 10 is provided with the diametrically opposed longitudinally disposed slots 12 in which is seated the terminal portions of the pin 14 disposed through the inner member 11. By this arrangement it will be at once self-evident that the intermediate section 7 is extensible so that no obstruction to the rotation of the mandrel M will be effected when the bearings 5 are moved longitudinally of the rods 3.

The outer extremity of the section 8 of the mandrel M is angular in cross section.

- as indicated at 15, and is insertible within an opening 16 in the coupler 17, said opening 16 being also angular in cross section. The coupler 17 is adapted to be engaged 5 with the crank shaft D of a motor of an automobile or the drive shaft of any other engine preferably of an internal combustion type, and is held to said shaft 8 through the medium of a set screw 18 or the like.
- 10 As disclosed particularly in Fig. 4 a coupler 17 co-acts with a motor of the Ford type and is secured to the crank shaft D after the conventional belt pulley has been removed. The inner end of the coupler 17 is 15 enlarged as at 31 to serve as a drive pulley for the fan F. The coupler 17 is also keyed to the shaft D through the medium of the pin 32 disposed through the enlarged portion 31 of the coupler 17 and the shaft 20 D as particularly illustrated in Fig. 5.
- As herein disclosed, the outer or free end portion of the section 6 of the mandrel M has affixed thereto a circular saw S adapted to co-act with the work table 19 suitably supported by the frame F. It is to be noted that the saw S may be properly moved relative to the table 19 in order to effect the requisite cut.
- While any means may be employed for 30 moving the bearings 5 longitudinally of the rods 3, I prefer to employ the arrangement disclosed in the accompanying drawings and wherein an arm 20 is provided which has at one end the diverging branches 21 pivotally 35 engaged with the bearings 5, while the opposite end portion of the arm is pivotally engaged, as at 22, with the upstanding lever 23. The lower end portion of the lever 23 is pivotally engaged, as at 24, with the frame 40 F and the lever 23 is provided with the pawl 25 co-acting with the rack 26 carried by the frame F, whereby it will be perceived that the bearings 5 may be readily held against movement upon the rods 3 in one direction.
- 45 The frame F is provided with a supplemental beam 27 which rotatably supports a crank 28 of the conventional type and which is provided with the clutch face 29 adapted to coact in a conventional manner with the 50 adjacent or free end portion of the section 6 of the mandrel M. It will be at once self-evident that when the section 6 of the mandrel M has been adjusted in a position in alinement with the clutch face 29, the same 55 may be readily engaged therewith in order to effect the requisite cranking of the motor with which the mandrel M is operatively engaged.
- As the particular construction of the 60 crank 28 and the specific coaction between the clutch member 29 and the adjacent end of the section 6 of the mandrel M forms no

particular part of my present invention, it is thought that a detail description thereof is unnecessary.

The section 6 intermediate the bearings 5 has affixed thereto a pulley 30 around which is adapted to be disposed a belt leading to any suitable driven element. When the section 6 of the mandrel M is in alinement with the clutch face 29 of the crank 28, the belt disposed around the pulley 30 is slack so that movement will not be imparted thereto by the pulley. When it is desired to drive the driven element, it is only necessary to 75 impart the requisite pull upon the lever 23 to tighten the belt coacting with the pulley 30. It will also be self-evident that when it is desired to stop the driven element it is only necessary to throw the lever 23 in an 80 opposite direction.

From the foregoing description, it is thought to be obvious that a power transmitting device constructed in accordance with my invention is of an extremely simple and 85 comparatively inexpensive nature and is particularly well adapted for use by reason of the convenience and facility with which it may be assembled, and it will also be obvious that my invention is susceptible of 90 some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A device of the character described 100 comprising a supporting structure, a bearing slidably engaged with the structure, a mandrel rotatably supported by the bearing, an end portion of the mandrel being provided with coupling means, and means carried by 105 the structure for imparting rotation to the mandrel.

2. A device of the character described comprising a supporting structure, a mandrel rotatably supported by the structure, an 110 end portion of the mandrel being provided with coupling means, means engageable with the coupling means for rotating the mandrel, and means carried by the structure and operable independently of the last named 115 means for imparting rotation to the mandrel, said means being normally out of engagement with the mandrel.

In testimony whereof I hereunto affix my signature in the presence of two witnesses. 120
JOHN QUINCY PARIS.

Witnesses:

L. C. COLLINS,
O. F. MORRIS.
